CASETON FOR YARN PACKAGES

Fred W. Paffen, Great Neck, N. Y., and Edward M. Engel, Bergenfield, N. J., assignors to Celanese Corporation of America, New York, N. Y., a corporation of Delaware

Application August 25, 1949, Serial No. 112,358

2 Claims. (Cl. 206—65)

1
This invention relates to cartons and relates more particularly to cartons for storing and shipping packages of yarn.

The bulk of the yarn produced in the textile industry is wound into packages, such as bobbins, cones, cheeses, pirns and the like. During the storing and shipping of these yarn packages they must be supported so as to prevent them from rubbing against each other or against the walls of the carton in which they are contained, since such rubbing would damage at least the outer layers of yarn on said packages. The cartons heretofore employed for storing and shipping yarn packages have included means, such as apertured inserts, for engaging the yarn packages so as to prevent movement thereof and damage to the yarn wound thereon. However, these cartons have been relatively expensive and have required a considerable amount of labor for their assembly and disassembly, thereby increasing the handling costs in storing and shipping the yarn packages. In addition, these cartons have failed to provide adequate support for the yarn packages, with the result that yarn damage frequently occurred, particularly when the loaded cartons were subjected to shocks during handling or shipping.

It is an important object of this invention to provide a carton for storing and shipping packages of yarn which will be free from the foregoing and other disadvantages of the cartons hitherto employed for this purpose, and which will be especially simple in construction and efficient in use.

A further object of this invention is the provision of a carton for storing and shipping packages of yarn which will engage and support said packages so as to avoid relative movement thereof and damage to the yarn wound thereon.

Other objects of this invention, together with certain details of construction and combinations of parts, will be apparent from the following detailed description and claims.

A preferred embodiment of our invention of a carton for storing and shipping cones of yarn will now be described with particular reference to the accompanying drawing wherein

Fig. 1 is a cross-sectional view of the carton showing the arrangement of the packages of yarn therein.

Fig. 2 is a cross-sectional view taken on the line 2—2 in Fig. 1 in the direction of the arrows.

Fig. 3 is a detail view, on an enlarged scale, showing the manner in which the packages of yarn are supported, and

Fig. 4 is a perspective view, on an enlarged scale, showing the fitting that engages the packages of yarn.

2
Fig. 4 is a perspective view, on an enlarged scale, showing the fitting that engages the packages of yarn.

Referring now to the drawing, the reference numeral 11 designates generally the protective cover of a carton which may be formed from corrugated board, cardboard or other suitable material and in which is contained a plurality of yarn packages, such as cones 12 comprising tubes 13 of conical shape having yarn 14 wound thereon. The cones 12 are arranged in superposed layers 15, 16, 17 and 18, each of which layers is supported on a shelf 19 having a plurality of regularly disposed apertures 22 extending therethrough. Positioned in the apertures 22 are fittings, indicated generally by reference numeral 23, comprising a base 24 having a rounded nipple 25 projecting from the under surface of said base and extending through the apertures 22, which nipple 25 is of such diameter as to engage snugly the top of the tube 13. An inwardly tapering wall 26, which is of such diameter and inclination as to engage snugly the base of the tube 13 projects from the periphery of the upper surface of base 24. The shelves 19 and the fittings 23 are each formed from a suitable organic plastic material such as, for example, cellulose acetate or other organic acid ester of cellulose and are joined together by means of a cement containing a solvent for the organic plastic material to form a strong autogenous bond. Because of the strength of the plastic material from which the shelves 19 and the fittings 23 are formed and because of the strength of the autogenous bond between said members, the shelves 19 may be reused repeatedly, thereby decreasing the cost of the cartons.

In packing the carton of our invention, the cones 12 are positioned on the shelves 19 with the base of the tube 13 of each of said cones snugly engaging the wall 26 of a fitting 23 to hold said cones against relative movement and damage to the yarn thereon. Then the shelf 19 with the cones 12 thereon is placed in the protective cover 11, forming the layer indicated by reference numeral 15, with the nipples 25 of said shelf resting on a liner 27 in said protective cover. A second shelf 19 with cones 12 thereon is then placed in the protective cover 11 to form the layer 16 with the nipples 25 of said shelf fitting snugly into the tops of the tubes 13 of the cones 12 in the layer 15. The layers 17 and 18 are formed and superposed on the layer 16 in similar manner. On top of the layer 18, there is placed a shelf 19, with the nipples 25 of said shelf

fitting snugly into the tops of the tubes 13 of the cones 12 in said layer to hold said cones against relative movement and damage to the yarn thereon. Then, a liner 28 is placed on top of said shelf and the carton is closed and sealed 5 in a manner well understood in the art.

It is to be understood that the foregoing detailed description is given merely by way of illustration and that many variations may be made therein without departing from the spirit of our 10 invention.

Having described our invention, what we desire to secure by Letters Patent is:

1. In a carton for storing and shipping superposed layers of yarn packages having conical cores, the combination with apertured shelves, of an organic derivative of cellulose, each adapted to support a layer of yarn packages, of fittings, of an organic derivative of cellulose, extending through the apertures in said shelves 20 and being cemented thereto form an autogenous bond for engaging said yarn packages to prevent relative movement thereof, said fittings comprising a downwardly extending nipple for reception within the top of the conical core of 25 the yarn package positioned on a shelf beneath the shelf having said fittings therein and, integral with said nipple, an upwardly extending inwardly-tapered, cup-shaped portion of greater diameter than said nipple for reception within 30 the bottom of the conical core of a yarn package positioned on the shelf having the fittings therein.

2. In a carton for storing and shipping super-

posed layers of yarn packages having conical cores, the combination with apertured shelves, of cellulose acetate, each adapted to support a layer of yarn packages, of fittings, of cellulose acetate, extending through the apertures in said shelves and being cemented thereto to form an autogenous bond for engaging said yarn packages to prevent relative movement thereof, said fittings comprising a downwardly extending nipple for reception within the top of the conical core of the yarn package positioned on a shelf beneath the shelf having said fittings therein and, integral with said nipple, an upwardly extending inwardly tapered, cup-shaped portion of greater diameter than said nipple for reception within the bottom of the conical core of a yarn package positioned on the shelf having the fittings therein.

FRED W. PAFFEN.
